UNITED STATES PATENT OFFICE.

HERMAN GOLDSMITH, OF NEW YORK, N. Y., ASSIGNOR TO THE AMERICAN TOBACCO COMPANY, OF NEW YORK, N. Y., A CORPORATION OF NEW JERSEY.

VACUUM CONTAINER

1,418,914.

Specification of Letters Patent. Patented June 6, 1922.

Application filed February 28, 1921. Serial No. 448,382.

To all whom it may concern:

Be it known that I, HERMAN GOLDSMITH, a citizen of the United States, and resident of New York city, in the county of New York and State of New York, have invented certain new and useful Improvements in Vacuum Containers, of which the following is a specification.

This invention relates to a container structure and more particularly to a container of the type in which the cover is hermetically sealed to the body of the container, the container being adapted to be exhausted to produce a vacuum receptacle and has special reference to the provision of such a vacuum container or receptacle in which the cover is hingedly connected to the body and in which the step of sealing the cover to the body will not interfere with the integrity of the hinge elements and in which the hinge is so housed or enclosed as to permit the production of a vacuum receptacle.

In the packaging of tobacco and other products it is the practice to provide a container in which all the walls are hermetically sealed to permit exhaustion of the air in the container after the packaging operation in order to produce a vacuum receptacle, in which the products may be kept and stored for an indefinite period of time without deterioration.

A form of container usually used for this purpose consists of a receptacle having a removable slip-on cover, the cover being provided with depending flanges frictionally fitting the body walls of the container, a "rip-strip" being provided for hermetically sealing the closely fitting flange edges to the container walls. In order to permit an effective seal between cover and body, the practice has been to provide covers with parts tightly fitting the container walls; and in order to secure this prior constructions have been limited, as far as I am aware, to removable slip-on covers. A difficulty with containers provided with such removable slip-on covers lies in the fact of cover removability, especially when used for packaging commodities such as tobacco, in which the product packaged is consumed only in portions from time to time. A removable cover especially when such cover is a tight fitting one, is difficult of return registration and replacement, such covers, moreover, being subject to liability

of misplacement and loss, leaving the unconsumed product remaining in the box subject to rapid deterioration.

To overcome the disadvantages of a removable cover, it has been found desirable to package the product in a container having a nonremovable cover in the form of a hinged cover. Considerable difficulty, however, has been encountered in the production of a container provided with a hinged cover which could be effectively sealed to the body walls of the container without destroying the integrity and utility of the hinge. Furthermore, the difficulties have been multiplied in the type of box construction in which the body walls are slotted for the production of the hinge pintle receiving ears or depressions, such slits being difficult to close, especially where a vacuum tin is required; it being necessary, furthermore, to close such slits without destroying the effectiveness of the hinge elements to permit free opening of the cover after breaking of the seal. After considerable experimentation I have devised a box construction in which the elements are related in a simple manner, yet in which I provide a hinged cover construction effectively hermetically sealed to the body walls of the container, the hinged cover being housed and protected during the sealing operation, in which the hinge elements are effectively sealed and in which, after the breaking of the seal, the cover may be freely opened and closed on its hinge.

Furthermore, in the manufacture of containers provided with slip-on covers, where quantity production is requisite, difficulty has been experienced in properly positioning the sealing or "rip-strip" for hermetically sealing same to the cover and walls, it having been found necessary to provide grooves or beads in the container body walls to facilitate rapid and accurate positioning of the "rip-strip" to the container body and cover. The provision of such grooves or beads necessitates additional manufacturing steps with a resulting increment added on to the ultimate cost of the container. I have found that the "rip" or sealing strip may be so constructed and related to the hinge elements of the cover that the cooperation of these elements during assembly for the sealing step will provide a ready means for locating and also locking the "rip-strip" in

proper registering position with respect to both the cover and body of the container.

The principal objects of my present invention therefore include, besides the provision of a hinged cover vacuum container; the provision of such a container in which the hinge elements are housed and protected during the sealing operation; the provision of such container in which the hinge cooperates with the sealing strip for readily locating and locking the latter in position during the assembling and sealing operations; the provision of such a container in which the hinge elements are fully operative after breakage of the seal; the further provision of a novel sealing strip and the provision of elements entering into the container structure which are relatively simple in construction and which may be manufactured with the fewest of operative steps to reduce the cost of container manufacture to a minimum.

To the accomplishment of the foregoing and such other objects as may hereinafter appear, my invention consists in the elements and their relation one to the other, as hereinafter particularly described and sought to be defined in the claims, reference being had to the accompanying drawings which show a preferred embodiment of my invention and in which

Figure 1 is a perspective view of a hermetically sealed container embodying my invention;

Figure 2 is a section on the line 2-2, Figure 1;

Figure 3 is a perspective view of a sealing strip designed to hermetically seal such a container as shown in Figure 1, and

Figure 4 is a view of a detail.

Referring to the drawings, the container comprises side walls 5, to which is connected the bottom 6 and the cover 7, the bottom 6 being preferably of the depressed type and provided preferably with a central opening 8 for a purpose to appear hereinafter. The cover 7 is preferably provided with downwardly extending flange portions 9 adapted to fit over the top portions of the side walls 5 when in closed position thereon.

In my present invention the cover is connected to the body side walls by any form of hinge construction, an approved form being here illustrated and consisting of an outwardly turned bead 10 forming part of one of the flanges 9 of the cover; the said bead enclosing a pintle 11, one of the body side walls 5 being provided with opposed slits 12, one of which is shown in Figure 4 of the drawings and outwardly extending depressions or ears 13 adapted to receive the pintle 11; these elements cooperating to form the hinge construction.

For the purpose of hermetically sealing the hinged cover to the body side walls I provide a sealing strip 14 which is of the

"rip-strip" type and formed of relatively soft and readily bendable or foldable material, the said strip being designed to pass entirely around the container, as clearly shown in Figure 1 of the drawings, the strip 70 preferably overlying the line of joint between the cover flanges 9 and the body side walls 5, the ends of the strip being arranged in overlying relation as shown at 15, this strip being connected to the depending cover 75 flanges and the side walls by soft solder or similar sealing means as shown at 16 and 17 respectively in order to close all the joints. One end of the strip 14 is bent back to provide a loop 18, shown in Figure 1 of the drawings, which loop is not soldered to the container and which is passed through a suitable key 19 by which the strip may be removed. A key may or may not be employed, as desired. When it is desired to break the 85 seal it is only necessary to roll the "rip-strip" back onto its key, if a key is used, tearing it completely away from the container, whereupon the cover 7 may be readily opened and closed upon its hinge. 90

In order to protect the hinge elements from the step of soldering the strip 14 along the lines 16 and 17 and in order to effectively seal the said hinge elements to permit of the production of a vacuum tin, I provide 95 the sealing strip with a hinge accommodating or receiving conformation, shown in the present instance as an elongated recess or depression 20, the said depression being arranged in overlying relation on the hinge 100 elements 10 to 13; this construction providing for housing the hinge elements and completely protecting the same from the soldering operation. When the strip 14 provided with the depression 20 is turned about 105 the side walls 5 of the container for the soldering operation, the depression 20 is positioned over the hinge elements, the co-operation between the depression 20 and the hinge elements providing centering means 110 for locating the strip 14 in proper position relative to the flanges 9 of the cover and the side walls 5 of the container and locking such strip in such centered position, preventing displacement thereof during the application of solder along the lines 16 and 17 as hereinabove referred to. 115

In the manufacture of the container the side walls and the hinged cover are first interconnected, the "rip-strip" being then arranged and soldered in overlying relation to the cover and the body, the resulting container shell with the open bottom being then shipped to the packer. The packer after placing the commodity to be packaged into 125 the open bottom container, positions the depressed bottom 6 on the container side walls, the bottom edges of the side walls being received by the annular pocket 21 formed in the bottom 6, the joint between the bottom 130

and the side walls 5 being closed as by dipping the container in a tank of solder. The air in the container is then exhausted through the opening 8 to produce a vacuum, the opening 8 being then closed by a drop of solder, as shown in Figure 2 of the drawings.

The operation and use of my device will, in the main, be apparent from the above detailed description thereof. It will be apparent that I have provided a hinged cover vacuum container in which all the joints are effectively hermetically sealed and in which after breaking the hermetic seal, a fully operative hinged box construction is permitted. Although I have shown my invention applied with the use of a well known form of hinge, it will be understood that the invention is not limited to any particular form 20 of hinge nor to any specific form of hinge accommodating depression, as obviously the contour of that part of the sealing strip that covers the hinge will depend upon the construction of the hinge itself. In its broader 25 aspect the invention resides in a vacuum container or tin having a hinged cover which is retained in position by means of a removable sealing or "rip-strip," which, when removed, permits the cover to be readily 30 opened and closed on its hinge.

While I have shown my device in the preferred form, it will be obvious that many changes and modifications may be made in the structure disclosed without departing 35 from the spirit of the invention, defined in the following claims.

I claim:

1. A metal container adapted to be exhausted to produce a vacuum receptacle; 40 said container comprising a body, a cover hinged thereto and means separate from the cover hermetically sealing the cover to the body, said means overlying and enclosing the hinge; the said means being adapted for 45 removal for breaking the seal, the cover after removal of said means being freely movable on its hinge.

2. A metal container comprising a body, a cover hinged thereto and a removable means 50 hermetically sealing the cover to the body of the container and overlying and protecting the hinge, whereby when the sealing means is removed the cover may be opened and closed on its hinge.

55 3. A metal container comprising a body, a cover hinged thereto and a removable sealing strip overlying the hinge and the free edge of the cover and hermetically sealing the hinged cover to the body.

60 4. In a metal container, the combination of an open top box body, a cover hinged thereto; said cover having depending flanges adapted to overlie the upper edges of the box body, and a sealing strip encircling the

body and overlying the free edge of the 65 cover including its hinge, and sealing material placed along the edges of the strip.

5. In a metal container, the combination of an open top box having a cover hinged thereto, with a "rip-strip" overlying the free 70 edge of the cover and having a depression to fit over the hinge; the said strip sealing the cover to the box.

6. As a new article of manufacture, a flat metallic sealing strip for a container 75 having a hinged cover, said strip adapted to overlie the free edge of the cover and having a portion thereof so formed as to conform to the shape of a hinge.

7. A flat metallic sealing strip for effecting a hermetic closure of a container having a hinged cover, said strip being adapted to encircle the container and provided with a recess in one portion thereof to receive the hinge when the strip is placed in position. 80

8. As a new article of manufacture, a "rip-strip" comprising a strap or band of relatively soft and readily foldable metal having a depression in a predetermined portion only thereof adapted to overlie and 90 house a projecting hinge on a container.

9. As a new article of manufacture, a metal container shell having an open bottom, a cover hinged thereto and removable means hermetically sealing the cover to the 95 shell; said means overlying the hinge.

10. As a new article of manufacture, a metal container body having an open bottom, the body being provided with opposed slits and outwardly protruding depressions 100 to accommodate a hinge pintle, a cover for the body having an outwardly turned bead carrying the hinge pintle, the said cover being hingedly connected to the body, and a "rip-strip" hermetically sealing the cover 105 to the body, said strip protectively enclosing and sealing the hinge.

11. A metal container comprising a body provided with opposed slits and outwardly protruding depressions in a side wall thereof for receiving a hinge pintle, a cover for the body having an outwardly turned bead carrying the hinge pintle; the said cover being hingedly connected to the body, and a sealing strip encircling the body and the 110 cover and hermetically sealing the cover to the body; the said strip being provided with a central depression fitting over the hinge bead and body depressions adapted to position and lock the strip over the cover and 115 body and to protect the hinge elements during the sealing operation; the said strip being removable to break the seal and to permit free movement of the cover on its hinge.

Signed at New York city, in the county of New York and State of New York, this 26th day of February, A. D. 1921.

HERMAN GOLDSMITH.
